UNITED STATES PATENT OFFICE

WILLIAM DEUTSCH, OF DETROIT, MICHIGAN

COMBINATION SHAVING SET

Application filed January 8, 1930. Serial No. 419,256.

The object of my invention is to produce a small, compact shaving kit, inclosed in a sealed case, suitable for packing in a traveling bag without soiling or injuring other articles placed therewith.

Another object is to produce a combination shaving set so designed that the casing sections may be readily converted into handles for the various shaving accessories.

10 A further object is to produce a combination shaving set designed with various recesses therein for receiving detached parts of the set therein.

15 A still further object is to produce a complete, compact shaving set that is simple in construction, easily and efficiently operated and that can be manufactured at a very low cost.

20 These several objects are attained in the preferred form by the construction and arrangement of parts more fully hereinafter set forth and described.

Similar parts on all drawings are marked by similar figures and letters.

25 Fig. 1 is an exterior view of the shaving set showing the inclosing casing and operating knobs mounted thereon.

Fig. 2 is a sectional view taken on the line 2—2 of the Fig. 1 showing the general arrangement of the operating parts in their folded position.

Fig. 3 is an end view of the casing operating knob taken along the line 3—3 of the Fig. 1.

30 Fig. 4 is an exterior view of the brush casing section showing the brush in its extended position.

Fig. 5 is an exterior view of the razor casing section showing the razor in its extended position.

35 Fig. 6 is a cross sectional view taken on the line 6—6 of the Fig. 1 showing the interior construction of the razor operating drum and connected mechanism.

40 Fig. 7 is a sectional view taken on the line 7—7 of the Fig. 1 showing the relative position of the razor post and attached razor head in its folded position.

50 Fig. 8 is a cross sectional view taken on the line 8—8 of the Fig. 4 showing the relative

position of the brush operating bar attached to the movable brush head.

Fig. 9 is an enlarged perspective view of the razor head in an open position showing the means for mounting a razor blade therein 55 and securely locking same.

Fig. 10 is a bottom view of the razor head taken on the line 10—10 of the Fig. 9 showing the locking slide mounted thereon and means for operating same.

Fig. 11 is a detail view of the special razor blade to be inserted within the razor head showing the means for holding same rigidly in place when locked therein.

60 In general my device comprises two tubular casing sections of equal diameters and of approximately the same length, each casing section being closed at one end by rotatably mounted operating knobs, the open casing ends being joined together by threaded 65 means and when assembled form a closed tubular case. Within one of the casing sections is mounted a slideable shaving brush head, capable of being drawn wholly within the casing or partially ejected therefrom through 70 connected mechanism actuated by the attached end operating knob. Likewise the other casing section contains a movably mounted safety razor device, capable of being moved in and out of the casing member 75 by attached mechanical means actuated by the connected end operating knob. By separating the casing sections at the central threaded joint, both the brush and razor sections may be quickly ejected from their 80 respective casing sections, ready for use in the ordinary manner for using similar shaving articles. The casing when closed, forms 85 a sealed container for all of the shaving accessories, suitable for packing.

90 I will now describe more fully the detailed construction of my device, referring to the drawings and the marks thereon.

95 The casings are preferably made of thin sheet metal, although they may be made of any other suitable materials such as hard rubber or similar materials if desired, and are formed in tubular sections —1— and —2— of approximately the same diameters, and with one section being preferably slight-

100

ly longer than the other. The casing section —1—, being the shorter section, is provided with an internal thread —a— at the open end thereof. The casing section —2— is provided with a corresponding external thread —b— at its open end, suitable for screwing the two sections together, forming a closed casing as shown in Fig. 1 of the drawings. The opposite end of the casing —1— is closed by the fixed end wall —c—, preferably formed as a part of the casing metal, and is provided with a centrally located hole —3— positioned concentric with the tubular casing axis. Mounted on the outside of the end wall —c— and adjacent thereto, is a circular operating knob —4—, made of metal or other suitable material, and is provided with a collar projection —d— on one side thereof, of a diameter to engage and fit the end casing hole —3— but free to turn therein. The knob —4— is formed with a threaded hole —5— positioned therein concentric with the casing axis. Within the threaded hole —5— is fixedly mounted the threaded end of a shouldered operating bar —6— screwed tightly therein and rotatable with the knob —4—. The operating bar —6— is formed with an external spiral groove —e— extending the entire length thereof, and is formed with a disc head —f— positioned near the open casing end. A lock washer —7— is mounted on the threaded shouldered end —h— of the operating bar —6— and tightly clamped against the knob collar projection —d— when the bar —6— is screwed tightly within the knob recess. The collar —d— being of a thickness to prevent clamping of the lock collar —7— on the casing end wall —c—, allowing free turning of the knob —4— and attached operating bar —6— thereon. Along one side wall of the casing —1— is formed an internal guide groove —8—, positioned therein parallel with the casing axis. Within the casing —1— is slidably mounted a shaving brush head —9—, made of hard rubber or other suitable material, having suitable brush bristles —10— securely imbedded therein in the usual manner for making shaving brushes, said bristles projected from one side thereof. The brush head —9— being capable of sliding within the inclosing tubular casing, is formed with a central opening —11— of a sufficient diameter to admit the operating bar —6— therethrough. The opening —11— is formed with an outer recess —12— concentric therewith, for receiving and fitting the end head —f— of the operating bar —6—, when the brush head —9— is in its outer position. Within one side of the brush head —9— is mounted a small driving pin —13—, positioned to project inside of the hole —11— and engage the spiral groove —e— of the operating bar —6—, and also projected outside the head —9— to engage the casing guide groove

—8—. As the knob —4— is turned in one direction the brush head —9— is forced out of the casing by the spiral operating bar —6— until the recess —12— engages the bar head —f— and securely locking the brush in that position. By reverse rotation of the knob —4—, the brush is drawn completely within the casing —1—.

The tubular casing —2— is opened at both ends, and is provided with an internal collar —14— inside the threaded end —b—, and also an internal key groove —15— at the opposite casing end. Along the side wall of the casing —2— is formed an internal guide groove —16—, extending nearly the entire length of the casing and parallel to the casing axis. Within the outer end of the casing —2— is fitted a hollow operating drum —17— of approximately one half of the casing length, said drum —17— being rotatably mounted therein by the ring key —18— engaging a circumferential groove —19— and the casing key groove —15—, the drum being free to turn thereon. The drum —17— is formed with a closed inner end —g— having a drum core —20— formed thereon and extending the entire length of the drum. Through the center of the core 20 is formed a guide passage —21— positioned concentric with the drum and casing axis. The outer end of the drum —17— is formed with a threaded section —h— projected outside of the casing end wall. A lock nut —22— and a turning knob —23— are tightly screwed on the threaded drum section —h—, said knob being fixedly attached thereto by the adjacent nut —22—. Within the guide passage —21— is mounted an operating bar —24— extending the full length of the core —20—, fitted therein but free to rotate within the guide passage. The operating bar —24— is formed with an external spiral groove —25— extending the entire length thereof, and is formed with a head frame —26— on the inner end, positioned outside of and adjacent to the drum end wall —g—. The head frame —26— is formed of a cylindrical disk section —k— of a diameter to fit the inner tubular casing walls but free to slide therein, and is formed with an annular groove —27— for engaging the end collar —14— of casing —2—, when said head frame is moved to its outer position. A guide pin —28— is mounted in the edge of the head frame —26—, positioned to engage the casing guide groove —16—, to prevent rotation of said head frame and attached operating bar —24— as the drum —17— is rotated by the attached knob —23—. Within the operating drum wall, preferably the end wall —g—, is mounted a drive pin —29—, positioned therein to engage the spiral groove —25— of the operating bar, for causing a longitudinal movement of the bar —24— as the drum —17— is rotated within casing —2—, thus forcing the

head frame —26— to its extreme position at the casing end. At the center of the head frame —26— is formed a rigid razor post —30—, made as a part of the head frame and

5 positioned concentric with the casing axis. The post —30— is formed with a hinge joint —31— at the outer end thereof, and carries pivotally mounted thereon a rectangular shaped razor block —32—, approximately 10 twice the length of the supporting razor post, said razor block being capable of being turned to either a parallel or a horizontal position thereon, and firmly held in either position by the angular stop wall —m— of

15 the post engaging one of the corresponding hinge walls —p— on the razor block, and also by the snugly fitted pivot joint, the razor head and post being of dimensions to retain said razor block wholly within the casing 20 —2— when folded therein. Pivotally attached to one end of the razor block —32— is a special blade clamp —33—, jointed there-

25 to at one end by the hinge wings —34— and pivot pin —55—, positioned to close over the razor block —32— and tightly clamp a thin double edged razor blade —35— therebetween. The blade clamp —33— is formed with projecting end wings —36— at the free end thereof, positioned similarly to the hinge wings —34— at the opposite end. The razor blade —35— is likewise formed with corresponding notches —37— at each end thereof for engaging the wing projections —34— and —36— and retaining said

35 blade in a rigid pre-determined position when tightly clamped therein. Along the outer edges of the end wings —36— are formed longitudinal grooves —38—, and which receive the curved edges —39— of the lock slide —40— therein when closed. The lock slide —40— is mounted on the under side of the razor block —32—, slidably thereon, projecting through the block slots —41—, and is clamped snugly thereto. The slide 40 —40— when moved to its locking position engages the pin head —42— which is securely mounted in the razor block wall, and retains the lock slide —40— firmly in its locking position.

50 By rotating the operating knob —23— in one direction the razor head frame —26— and attached razor is extended outside the casing end as is indicated in Fig. 5 of the drawings, and when turned at right angles 55 to the razor post —30—, is ready for shaving in the ordinary manner. When the razor head is folded parallel to the razor post —30— and the operating knob —23— is rotated in the opposite direction, the razor head frame is readily withdrawn within the casing section, ready for closing and packing.

60 Within the recess —43— of the operating drum —17—, may be placed extra razor blades —44—, for convenient carrying. Also, within the recess —45—, behind the razor

block —32—, may be placed a small tube of shaving cream —46—, also for convenient carrying, and for providing a complete shaving set within the inclosing tubular casing.

70 It is apparent that my device is subject to various modifications in both mechanical structure and design, and I claim as my invention the device as herein shown and any such modification thereof that is substantially a substitution therefor.

75 Having fully described my combination shaving set, what I claim as my invention and desire to secure by Letters Patent is;

Claims:

1. A combination shaving set adapted for 80 traveling purposes, comprising two jointed casing sections, a shaving brush slidably mounted within one of the casing sections, a razor slidably mounted within the other casing section, and means formed on the casing sections for joining the ends thereof together.

85 2. A combination shaving set adapted for traveling purposes, comprising two jointed tubular casing sections, a shaving brush slidably mounted within one of said casing sections, mechanical means mounted therein for displacing said shaving brush within said casing section, a razor slidably mounted within the other casing section, mechanical 90 means mounted thereon for displacing said razor within said casing section, and means mounted on the casing sections for joining said sections together.

95 3. A combination shaving set adapted for 100 inclosing within a sealed casing, comprising two tubular casing sections having means for joining same together at the ends, a shaving brush head with brush attached slidably mounted within one of said casing sections, a spiral operating shaft rotatably mounted within said casing section and splined to said brush head, means mounted on said spiral shaft for causing rotation thereof within said casing for displacing said brush head there- 105 in, a razor section slidably mounted within the other casing section, a spiral shaft fixedly attached to said razor section, mechanical 110 means mounted within said casing section and splined to said spiral shaft for causing 115 a displacement of said razor section within the casing.

4. A combination shaving set, comprising 120 a tubular casing formed of two tubular sections joined together at the ends, a shaving brush head with brush attached slidably mounted within one of said casing sections, said brush head being formed with a central hole therethrough, a spiral operating shaft rotatably mounted in said casing section and extended through said brush head hole and splined thereto, an operating knob mounted on the outer end of said spiral shaft outside the casing end, for rotating said shaft and causing displacement of said brush head 125 129

within the casing section, a razor section slidably mounted within the other casing section, said razor section having a spiral shaft fixedly mounted thereon, an operating drum rotatably mounted within said casing section and inclosing said spiral shaft and splined thereto, an operating knob mounted on said operating drum for causing rotations thereof and a displacement of the connected spiral shaft and razor head.

5. A combination shaving set comprising a tubular casing formed of two tubular sections jointed together endwise, a guide groove formed along the side wall of both of said tubular casing sections parallel to the casing axis, a brush head with brush attached slidably mounted inside of one of the tubular casing sections, said brush head being formed with a central hole therethrough, a spiral operating shaft rotatably mounted within said casing section and projected through the brush head hole and splined thereto, means mounted in said brush head for engaging the casing guide groove, an operating knob fixedly attached to said spiral shaft outside the casing end for causing rotation of said spiral and a displacement of the attaching brush within the casing, a razor section slidably mounted within the other casing section and splined to the casing side guide groove, a spiral shaft fixedly mounted on said razor section positioned concentric with the casing axis, an operating drum rotatably mounted within the casing section inclosing said spiral shaft and splined thereto, an operating knob mounted on the outer end of said operating drum outside the casing end for causing rotation of said drum and displacement of the connected razor section within the casing.

10. 15. 20. 25. 30. 35. 40.

In witness whereof I sign these specifications.

WILLIAM DEUTSCH.
